(57) CLAIM

The ornamental design of a portable animal treat dispenser, as shown and described.

DESCRIPTION

FIG. 1 is a perspective view from the top right of the portable animal treat dispenser of my new design;

FIG. 2 is a right side elevation view thereof;

FIG. 3 is a front elevation view thereof;

FIG. 4 is a rear elevation view thereof;

FIG. 5 is a top plan view thereof;

FIG. 6 is a bottom view thereof; and,

FIG. 7 is a front elevation view thereof with the portable animal treat dispenser squeezed to an open position.

The broken lines shown in the drawings are for illustrative purposes only and form no part of the claimed design.
